HOUSING FOR TRANSDUCERS FOR TRANSFORMING GRAPHICAL DATA INTO ELECTRICAL VOLTAGES FOR INPUT INTO A COMPUTER OR SIMILAR ARTICLE

Lincoln P. Rosay, Tustin, Calif., assignor to Bolt Beranek and Newman Inc., Cambridge, Mass.

Filed Sept. 22, 1965, Ser. No. 87,109

Term of patent 14 years

(Cl. D26—5)

Fig. 1.

Fig. 2.

Fig. 3.

FIG. 1 is a top plan view of a housing for transducers for transforming graphical data into electrical voltages for input into a computer or similar article,

FIG. 2 is a side elevational view, the opposite side being substantially a mirror image thereof; and

FIG. 3 is a front elevational view thereof.

The dominant features of my new design are shown in solid lines in the drawing, the broken lines showing of a pen and coupling being for illustrative purposes only.

I claim:

The ornamental design for a housing for transducers for transforming graphical data into electrical voltages for input into a computer or similar article, as shown and described.
